SAFETY RAZOR WITH A COMB MEMBER
CO-OPERATING WITH ONE OR MORE
CUTTERSPeter Harald Pedersen, Copenhagen, and Herman
Nielsen, Buddinge pr. Soborg, Denmark; vested
in the Alien Property CustodianApplication May 7, 1942, Serial No. 442,096
In Denmark May 10, 1941

2 Claims. (Cl. 30—43)

Razors are known which work according to the principle known from hair cutting machines, there being effected a cutting of the hairs between a comb member fitted with sharp-edged openings and a cutting member. The cutters and the comb member are movable in relation to each other in close contact with each other, so that a cutting action is effected. The motion may be effected by hand, a resilient lever being actuated by hand, but is now more frequently effected by motor power.

In the newer motor-driven razors of this kind the comb member is stationary, while the cutting member which usually has a ring of cutters, is able to move in its own plane in close contact with the inner surface of the comb member. In contradistinction to what is the case in hair cutting machines, the comb member must be very thin in order that the rest of the beard hairs remaining after the shave shall not be of any considerable length, and this for one thing is a reason why the comb member generally has not the shape of a comb any more, which would be far too unstable, but is shaped as a surface with slits or openings. The slits may e. g. be parallel when the cutting member has a reciprocating motion, or radial when the cutting member rotates in a plane parallel to the inner surface of the comb member. Similarly we do not, when in the following the term "comb member" is used, refer to the shape of the member, which need not bear any resemblance to a comb, but only to its action which is the same as the action of the really comb-shaped members in the hair cutting machines, from which the before mentioned razors have developed.

The aim of this invention is now a razor with a comb member co-operating with one or more cutters and furnished with openings, in which razor the comb member is freely movable in relation to the razor, whereby the relative motion between the comb member and the cutter or cutters, by which the cutting-off of the beard hairs is effected, is effected by the comb member, when the razor is moved across the skin, being held, in part by its friction against the skin, in part by the projection of the beard hairs into the openings of the comb member.

Hereby is attained in part that the use of motor power may be altogether avoided, in part that the comb member, when the razor is moved across the skin, will not as in the hitherto known razors slide across the skin, but will on the contrary rest firmly in relation to it, whereby the beard hairs will easily find their way in through the comb

openings, while at the same time an easy and gentle shave is obtained.

The comb member may be rotatable around a spindle in the razor, whereby the comb member performs a rotative motion during the shave. The cutter or cutters are fitted stationarily or so as to be able to move only in a slight degree inside the comb surface, which has the advantage that the construction is thereby made simple. The comb member may e. g. have the form of a cylinder.

In order to attain the play-free contact necessary for a gentle cutting of the beard hairs between the cutter or cutters and the inner surface of the e. g. drum-shaped comb member, the cutter or cutters may be held on to the latter by spring pressure. This may, however, entail the drawback that the beard hairs, which may be only partly cut through at the moment when the travel of the razor across the skin is stopped, will stick in the razor, so that a pull is exerted in the hairs when the razor is removed from the skin. In order to avoid this drawback the razor may be arranged so that the geometrical axis of the drum may be able to move slightly in relation to the cutting edge or cutting edges, so that the inside of the drum may get out of contact with the cutting member when the razor is not held on to the skin, but on the other hand will be held in close contact with the cutting edge or cutting edges, when the razor is held pressed against the skin.

In the following the invention will be further explained in connection with the description of some embodiments which are given only as examples, to which the invention is not bound, and which are shown schematically on the drawing, on which

Fig. 1 shows an embodiment of the new razor with a drum-shaped comb member, shown in perspective view,

Fig. 2 an embodiment of the holder and drum with parts fitted in it, partly in sectional view through the axis of the drum,

Fig. 3 the same embodiment in a section at right angles to the axis,

Fig. 4 another embodiment of the razor, likewise with a drum-shaped comb member, in partly sectional view through the axis of the drum,

Fig. 5 the same in a section at right angles to the axis,

Fig. 6 an embodiment of the cutting member mounted on its spindle,

Fig. 7 is a sectional view of the same,

Figs. 8, 9, and 10 another embodiment of the

cutting member, in side elevation, seen from above, and in sectional view respectively,

Fig. 11 a third embodiment of the cutting member in a section at right angles to the axis, and

Fig. 12 an embodiment of the razor with a conefrustum-shaped comb member, partly in sectional view.

1 in Fig. 1 is the hoop-shaped holder, 2 a handle, and 3 the drum-shaped comb member. The drum can rotate around a spindle 4 accommodated in the hoop, and the shaving is effected by the drum being rolled across the bearded skin. The drum 3 has sharp-edged openings 5 through which the beard hairs may project into the interior of the drum. Here one or more cutters, not shown, are in contact with the smooth inner surface of the drum. Care must be taken during the shave that the razor is held in such a position that the cutter is situated just inside the surface of the drum 3 that is in touch with the skin. To facilitate this there may be several cutters, or the cutters may be adjustable in relation to the holder. As there are limitations as to how large a part of the cylinder surface the openings 5 in the drum may take up, it will as a rule be possible during each cutting action to cut off only part of the beard hairs within the surface of the skin, across which the razor has been moved, for which reason the operation must be repeated some times, which may, however, be done easily and gently, as no soap or other shaving means is required.

In the embodiment shown in Figs. 2 and 3 one branch 6 of the holder is connected to the spindle 4 at one side, while the other branch 7 of the holder can turn in a joint 8, so that it can be turned to one side, so that the drum may be taken out when the razor is to be cleaned.

The drum 3 with openings 5 is in rigid connection with an end plate 9, which may be turned around and at the removal be shifted along the spindle 4. The other, open end of the drum is pushed in over a disc 10 that is accommodated rotatably on the spindle 4. A cutter holder 11 with a number of staying discs 12 is fitted rigidly to the spindle 4. In the said staying discs and in the cutter holder a slit 13 is milled out, in which a cutter 14, which is from behind stayed by a spring 15, is inserted. When the parts are fitted into their places as shown, the cutter 14 will rest with a slightly resilient pressure against the inner surface of the drum 3. By turning the branch 7 the drum may be taken off, and the cutter and the inner space of the drum cleaned of hairs.

In the embodiment shown in Figs. 4 and 5 the cutters 14 are accommodated so as to be able to turn around a pin 16 in one branch of the holder 1. At the back the cutter has side extensions 17, one of which is accommodated around the pin 16, while the other engages with a fork 18 in the other branch of the holder. On the cutter is inserted a drum holder 19 which has a milled-out recess 20 into which the cutter fits and the depth of which is slightly larger than the breadth of the cutter. Just like the cutter holder 11 in Figs. 2 and 3 the drum holder 19 has protruding staying discs 12. The ends of the drum holder are turned so as to form bearing surfaces, in part for the end plate 9 rigidly connected to the drum, in part for the disc 10 which stays the other end of the drum. By turning the cutter around the pin 16 the drum may be taken off.

The mode of operation of the embodiment shown in Figs. 4 and 5 is as follows. When the razor is pressed against the skin, the drum and

the drum holder yield to the pressure, so that the inner surface of the drum gets in close contact with the cutting edge of the cutter 14. When, however, the razor is not pressed against the skin, the drum holder 19, as the milled-out recess 20 of the latter has a depth that is larger than the breadth of the cutter 14, may be shifted so much that the inner surface of the drum gets out of contact with the cutting edge, so that e. g. no jamming of the beard hairs may take place. This mutual shiftability or mobility between the geometrical axis of the drum and the cutting edge has proved very expedient and may also be effected by other means, e. g. by the drum being accommodated with a certain suitable play.

In Figs. 6 and 7 is shown another embodiment of the cutting member, the latter having a number of cutting edges 21, in the figure six, which are placed in a star formation. The cutting member 20 may as shown be inserted on a non-round centre piece 33 of the spindle 4. When, as shown, the non-round centre piece is hexagonal, any of the cutting edges may, as it be desired, be placed in the positions that are preferably used during the shave.

In Figs. 8, 9, and 10 is shown a cutting member which has many cutting edges 21 placed obliquely in relation to the direction of motion of the drum surface.

Finally in Fig. 11 is shown a cutter holder 23 mounted rigidly on the spindle 4, which cutter holder carries a changeable cutter 24 formed as a thin blade.

In Fig. 12 the comb member consists of a plate-shaped surface with a flat central part 25 and a conical outer part 26 which is the comb surface proper and which is therefore provided with openings 5. The comb member is fitted so as to be able to turn around a pin 27 at the end of the handle 2. The latter carries on its side by means of an arm 28 a cutter holder 29 with a cutter 30 in such a position, that when the comb member is pressed lightly against the skin with the part in line with the cutter it will be brought to rest with its inner surface against the cutter all along the edge of the cutter.

As to details the invention may be constructed in many other ways than those shown and described without getting beyond its scope. Thus 50 the comb member may have many other shapes, e. g., be conical, ball-shaped, spindle-shaped, or shaped as a cylinder sector, rotatable in a way similar to that of the drums shown, but over an angle smaller than 360°. The openings 5 in the comb member may consist of a very large number of small, e. g., round holes which must be sharp-edged on the inside, or of slits, which may e. g. run parallel or in one or more oblique directions to the axis of the drum or the generatrix of the e. g. conical part 26.

The rolling motion of the comb member across the skin is ensured by the penetration of the beard stubbles into the holes on the surface of the drum, whereby slipping of the comb member is prevented, the stubbles acting like the teeth in a rack, thereby offering the necessary resistance for the cutting of the beard hairs.

We claim:

1. The combination in a razor of a handle, a U shaped holder member secured to one end of the handle, one of the arms of the U shaped member being provided with a forked end, a pivot pin mounted near the end of the second arm of the U shaped member, a cutter having one of its ends pivotally mounted on said pin whereby

may be swung about said pin into operative and inoperative position, the end of said cutter away from said pin being detachably connected to the forked end of said U shaped member, a cutter holder which provides a comb support slidably engaged with the cutter and extending lengthwise thereof, and cylindrical comb means detachably and rotatably mounted on said cutter holder.

2. The combination in a razor as claimed in claim 1 wherein the cutter holder is provided with bearing surfaces at its opposite ends and wherein said comb means comprises a hollow cylindrical member provided with a plurality of openings through the body thereof through which hairs project during operation of the razor, a pair of

5 discs, one of said discs mounted for rotation on the bearing surface of said cutter holder which is adjacent the pivot pin for the cutter holder, one end of said cylindrical member fixed to the second disc, said cylindrical member being slipped over said cutter holder when mounted for operation and said cylindrical member when mounted over the cutter having its free end and the rotatable disc adjacent said pivot pin engaged with each other and the disc fixed to the cylindrical member rotatably supported on the bearing surface at the end of the cutter holder most distant from said pin.
